STRUCTURAL NAILING MEMBER

Charles E. Wallis, Wauwatosa, Wis., and James J. Shanley, Grosse Pointe, Mich., assignors to National Steel Corporation, a corporation of Delaware

Application December 2, 1944, Serial No. 566,366

13 Claims. (Cl. 189—37)

1

The present invention relates to improvements in structural nailing members formed from sheet metal and more particularly relates to such structural members constructed and arranged for receiving and retaining nail and nail-like elements for construction purposes.

In recent years, there has been an increasing amount of relatively lightweight steel frames used for construction purposes. In this type of framing, structural members cold formed from hot or cold rolled steel strips are substituted for wood members or the old fashioned hot rolled steel structural members. Where the structural members are substituted for wood, the type of construction usually calls for the nailing of flooring, furring, sheathing and the like to the structural members constituting the frame in order to produce a completed structure. An ever present problem in this type of structure has been the relative expense of the metal structural members as compared to the cost of the wooden counterparts so that the problem is mainly one of economics and efficient fabrication of the structural members. The present invention provides a form of structural member which is the essence of simplicity relative to fabrication methods and at the same time presents the requisite strength with the lightest possible gauge of metal.

It is to be understood that although steel is specifically referred to herein, any other metal practical and economical under the circumstances of use will be just as suitable.

It is an object of the present invention to provide an improved structural member.

A further object of this invention is to provide a relatively rigid and lightweight structural member formed from a single strip of steel.

Another object of the present invention is to provide a structural nailing member of an improved construction including novel nail retaining means.

In a preferred embodiment of the present invention, the structural member is formed from a single steel strip and includes a web, a flange along one side of the web, and a nail guiding element parallel with and spaced from the web to form a nailing groove therebetween which bends the nail in the plane of the groove. Before bending the strip, series of nail retaining, relatively small bosses and relatively large protuberances are formed in the strip so that after bending the strip to form the structural member, these nail retaining elements project into the nailing groove. The opposed relatively large protuberances are spot welded together to form an integral structure. Relatively small entering perforations are formed in the flange and open into the nailing groove.

This structural nailing member has numerous advantages over the nailing members of the prior

art. The nail retaining bosses and protuberances are formed in the strip before bending and due to the fact that the structural member is formed from a single piece of steel, they will register properly with each other in the nailing groove of the finished article. The entering perforations and the nail guiding bosses are relatively small, numerous and so shaped that a nail will readily enter the nailing groove even though the nail is not in perfect alignment therewith. The relatively large protuberances provide good spot welding construction and are located in that portion of the nailing groove which is spaced from the flange. The shape and alignment of these protuberances are such that the welding connection is spaced from the flange and does not interfere with entry of the nail as is the case in many of the structural members heretofore suggested. The fact that the upper portion of the nailing groove is held together by the integrality of the bent strip and that the lower portion of the groove is held together by the spot welding provides a relatively rigid structure in which the elements will not be spread apart by a nail entering the nailing groove.

These and other objects and advantages of this invention will become more apparent from the following detailed description and the accompanying drawings in which:

30 Figure 1 is a cross sectional view of one form of a structural member embodying the features of the present invention;

Figure 2 is a plan view of a portion of a steel sheet from which the structural member of Figure 1 may be formed;

Figure 3 is a plan view of a portion of the structural member of Figure 1;

Figure 4 is an enlarged, partial view in section taken along line 4—4 of Figure 5, showing a wooden member nailed to the structural member of Figure 1;

Figure 5 is an enlarged, partial view in section taken along line 5—5 of Figure 4;

Figure 6 is a partial view in section taken along line 6—6 of Figure 4; and

Figure 7 is a partial view in section showing the construction of a portion of the structural member prior to welding and is taken along line 7—7 of Figure 4.

Referring to the drawings, a structural member 10 is formed from a single metal sheet or strip 11. In the embodiment shown in the drawings, the metal sheet 11 is bent to form a structural member having an I-shape in cross section. It will be apparent that a T-shape section is included in the present invention. Any other structural shape can be employed within the limits of the invention defined by the accompanying claims.

In the embodiment shown in the drawings, Fig-

ure 2 shows approximately half of the sheet or strip 11 which is formed into the I-beam 10, it being understood that the other half of the sheet 11 is a reversed duplicate of the portion shown. The sheet 11, which may be either hot or cold rolled steel, has formed therein series of protuberances 12 and bosses 13. Each protuberance 12 is formed with a raised dimple 14, as shown more clearly in Figures 2 and 7. Certain bosses 13 are formed with extended, raised guide portions 15, the purpose of which will be more fully herein-after described in detail. After these bosses and protuberances have been formed, the strip is bent along the lines 17, 18, 19 and 20 so as to form a web element 21, a flange 22 along one edge of the web element 21, and a nail guiding element 23 spaced from and parallel with the web 21 to form a nailing groove 24 therewith which extends in a direction parallel to the web 21.

Bending of the strip 11 brings the rows of bosses 13 opposite each other and brings the protuberances 12 to positions opposite each other in the nailing groove 24 as shown. The protuberances 12 are welded together at the dimples 14 to form the spot welds 27. The excess metal in the dimple 14 melts down sufficiently so that the opposed faces of the protuberances are brought together. The frustro-conical entering perforations or passages 16 are formed in the flange 22 after the strip 11 has been bent and are in line with and open into the nailing groove 24. The perforations 16 are relatively small and closely spaced so that a nail will readily enter the nailing groove 24 and are preferably formed in the flange 22 after the strip 11 has been bent but may be formed in the strip 11 prior to bending as indicated by broken lines in Figure 2, though this tends to form a relatively weak zone along which the strip may bend during the forming operation. The other half of the substantially flat sheet 11, not shown, is bent and then spot welded in a similar manner and at the same time to form the other half of the I-beam shown in Figure 1 and like reference numerals have been applied to the corresponding parts.

To further strengthen the beam 10, the sheet 11 may be bent to form corrugations 31. Other ribs or corrugations may be formed or they may be omitted depending, at least in part, on the thickness of the sheet 11 and the stresses which the beam 10 must support.

The opposed series of relatively small bosses 13 are so positioned as to be opposite each other after the sheet 11 has been bent to form the I-beam 10. Each adjacent pair of bosses form a nail guiding passage 25 therebetween that is substantially in line with a corresponding one of the entering openings 16 so that the opening 16 and its corresponding nail guiding passage 25 will maintain a nail entering the nailing groove 24 substantially normal to the flange 22. The series of protuberances 12 are also so positioned as to be opposite each other and to extend across the nailing groove 24 of the structural member. Each protuberance 12 provides a pair of diverging nail bending walls 28 so that the converging nail bending walls 28 of two adjacent protuberances form therebetween a funnel shaped entrance 29 to a nail receiving passage 30. The funnel-shaped entrance 29 extends across a plurality of the nail guiding passages 25 and the apex of the entrance 29 is sufficiently blocked by one of the bosses 13 so that a nail cannot enter the nail receiving passage 30 without first striking one of the nail bending walls 28 of one of the nail clinching abut-

ments 12. The nail guide 15 prevents a nail from turning back on itself after striking the nail bending wall 28 and also prevents a nail from entering passage 30 without first striking one of the nail bending walls 28.

Referring more particularly to Figures 4 and 6, a board 32 or other member, may be readily fastened to the structural member 10 by means of a nail 33. The nail 33 is forced through the board 32 at a point in the same plane as the series of openings 16 and in a direction substantially normal to the flange 22 and through one of the entering passages 16 into the nailing groove 24. The forward extremity 34 of the nail 33 is then forced through the passage 25 between adjacent bosses. The openings 16 are relatively close to each other so that if the nail 33 is started through the board 32 at any point in the plane of the groove 24 and the series of openings 16, then the nail 10 will readily pass through one of the openings 16 even though the nail 10 is not directly in line with any one opening 16. The opening 16 preferably is smaller than nail 33 so that the wall of the opening 16 grips the nail as do the bosses 13 so as to maintain the nail normal to the plane of the flange 22.

After the forward extremity 34 of the nail 33 has passed through the nail guiding passage 25, it strikes one of the nail bending walls 28 so that the forward extremity 34 is bent and is then guided into the nail receiving passage 30 by the nail guide 15 where it is held against withdrawal by being in holding engagement with the bottom surface 26 of the adjacent nail clinching abutment or protuberance 12. Thus, each two adjacent protuberances form a pair of upper converging nail bending walls 28 therebetween for bending the nail 33 in the plane of the groove 24. When the forward extremity 34 of nail 33 is driven into nailing groove 24, the forward extremity 34 strikes a nail bending wall 28 of one of the protuberances 12 and is bent into holding engagement with the bottom surface 26 of the adjacent protuberance 12 which holds the nail against withdrawal by resistance of the bent nail extremity 34 to straightening. The two adjacent protuberances 12 coact to both bend the forward extremity 34 and to hold it against withdrawal. The clinched nail 33 is gripped or held in place at three locations, which are (1) at the nail guiding passage 16, (2) between adjacent bosses 13 and (3) by the adjacent protuberance 12.

This construction has numerous advantages. The bosses 13 and the protuberances 12 are formed in the strip 11 before it is bent and after the strip has been bent, these raised portions are in proper alignment and there is little, if any, chance that they will not register properly. By making the bosses 13 and the perforations small, the nail readily enters the nailing groove and the head end portion of the nail does not bend as it may in those structural members where entry of the nail into the nailing groove is greatly impeded. By having the protuberances 12 relatively large, they can be readily spot welded together without the weld spot extending into the nail passage as would be the case if the protuberances were small. Further, this construction results in the formation of a desirable, rigid type of nailing groove 24 in that the upper portion of the nailing groove is held together by the integrality of the member and the lower portion of the groove is held together by the spot welds.

Having described one embodiment of our in-

vention, it is obvious that various modifications may be made in the structure shown in detail without departing from the spirit or scope of our invention except as defined in the accompanying claims. For example, staples may be substituted for nails 34 and the bosses and protuberances may be formed in the sheet 11 after bending instead of before bending and the nail guide 15 may be separated from the corresponding boss 13 or may be omitted.

We claim:

1. A structural nailing member for receiving and retaining nails, staples and the like, said structural member comprising a web element; a flange extending along one side of said web element; a nail guiding element parallel with and spaced from said web element to form a nailing groove therewith; guide means for maintaining a nail driven into said nailing groove normal to said flange, said guide means including a series of nail entering passages in said flange opening into said nailing groove, the wall of each entering passage gripping a nail entering said nailing groove through the passage, and a series of nail gripping bosses formed on one of said elements, each pair of adjacent bosses forming a nail guiding passage substantially in line with one of said entering passages; and means for bending the forward extremity of a nail in the plane of said groove and for holding the same against withdrawal by resistance of the bent nail extremity to straightening, said last mentioned means including a series of nail bending and holding protuberances, each adjacent two protuberances forming a pair of converging nail bending walls therebetween and coacting to bend and hold a nail.

2. A structural nailing member for receiving and retaining nails, staples and the like, said structural member comprising a web element; a flange extending along one side of said web element; a nail guiding element parallel with and spaced from said web element to form a nailing groove therewith; guide means for maintaining a nail entering said nailing groove normal to said flange; and means for bending the forward extremity of a nail in the plane of the nailing groove and for holding the same against withdrawal, said last mentioned means including a series of protuberances formed on one of said elements, each two adjacent protuberances having a nail receiving passage therebetween and forming a pair of straight converging nail bending walls therebetween, the converging nail bending walls defining a funnel shaped entrance to the nail receiving passage so that the forward extremity of a nail driven into the nailing groove and into a nail receiving passage will strike against the nail bending wall of one of the protuberances and be bent in the plane of the groove and into holding engagement with an adjacent protuberance which holds the nail against withdrawal by resistance of the bent nail extremity to straightening.

3. A structural nailing member for receiving and retaining nails, staples and the like, said structural member comprising a web element; a flange extending along one side of said web element; a nail guiding element parallel with and spaced from said web element to form a nailing groove therewith; a series of entering passages in said flange opening into said nailing groove; a series of nail gripping bosses formed on one of said elements, each adjacent pair of bosses forming a nail guiding passage therebetween; and means for bending the forward extremity of a nail in the plane of the nailing groove and for holding the same against withdrawal, said last

mentioned means including a series of protuberances each having a pair of upper diverging nail bending walls and a bottom nail holding wall, each two adjacent protuberances having a nail receiving passage therebetween and forming a pair of converging nail bending walls therebetween defining a funnel shaped entrance to the nail receiving channel, the funnel shaped entrance extending across a plurality of said nail guiding passages and having its apex substantially in line with one of said bosses so that the forward extremity of a nail driven into the nailing groove will strike against the nail bending wall of one of the protuberances and be bent into holding engagement with the bottom wall of an adjacent protuberance which holds the nail against withdrawal by resistance of the bent nail extremity to straightening.

4. A structural nailing member for receiving and retaining nails, staples and the like, said structural member comprising a web element; a flange extending along one side of said web element; a nail guiding element parallel with and spaced from said web element to form a nailing groove therewith; guide means for maintaining a nail driven into said nailing groove normal to said flange, said guide means including a series of nail entering passages in said flange opening into said nailing groove, the wall of each entering passage gripping a nail entering said nailing groove through the passage, a series of nail gripping bosses formed on said web element, and a series of similar bosses formed on said nail guiding element; said two series of bosses being opposite each other and each two opposed series of adjacent bosses forming a nail guiding passage substantially in line with one of said entering passages; and means for bending the forward extremity of a nail in a plane of said groove and for holding the same against withdrawal by resistance of the bent nail extremity to straightening, said last mentioned means including a series of nail bending and holding protuberances on said web element and a similar opposite series of protuberances on said nail guiding element, each two opposite pairs of adjacent protuberances forming a pair of converging nail bending walls therebetween and coacting to bend and hold a nail.

5. A structural nailing member for receiving and retaining nails, staples and the like, said structural member comprising a web element; a flange extending along one side of said web element; a nail guiding element parallel with and spaced from said web element to form a nailing groove therewith; guide means for maintaining a nail entering said nailing groove normal to said flange; and means for bending the forward extremity of a nail in the plane of the nailing groove and for holding the same against withdrawal, said last mentioned means including a series of protuberances formed on one of said elements and a second similar series of opposite protuberances formed on the other of said elements, each two adjacent pairs of opposite protuberances having a nail receiving passage therebetween and forming a pair of straight, converging nail bending walls therebetween, the converging nail bending walls defining a funnel shaped entrance to the nail receiving passage so that the forward extremity of a nail driven into the nailing groove and into a nail receiving passage will strike the nail bending wall of one pair of opposite protuberances and be bent in the plane of the groove and into holding engagement with an adjacent

pair of opposite protuberances which holds the nail against withdrawal by resistance of the bent nail extremity to straightening.

6. A one-piece structural member formed from a single metal sheet for receiving and retaining nails, staples and the like, said structural member comprising a web element; a flange integral with and extending along one edge of said web element; a nail guiding element integral with said flange, said nail guiding element being spaced from and parallel with said web element to form a nailing groove therewith; guide means for maintaining a nail driven into said nailing groove normal to said flange, said guide means including a series of nail entering passages in said flange opening into said nailing groove, the wall of each entering passage gripping a nail entering said nailing groove through the passage, and a series of nail gripping bosses formed on one of said elements, each pair of adjacent bosses forming a nail guiding passage substantially in line with one of said entering passages; and means for bending the forward extremity of a nail in the plane of said groove and for holding the same against withdrawal by resistance of the bent nail extremity to straightening, said last mentioned means including a series of nail bending and holding protuberances, each adjacent two protuberances forming a pair of converging nail bending walls therebetween and coacting to bend and hold a nail.

7. A one-piece structural member formed from a single metal sheet for receiving and retaining nails, staples and the like, said structural member comprising a web element; a flange integral with and extending along one edge of said web element; a nail guiding element integral with said flange, said nail guiding element being spaced from and parallel with said web element to form a nailing groove therewith; and means for bending the forward extremity of a nail in the plane of the nailing groove and for holding the same against withdrawal, said last mentioned means including a series of protuberances formed on one of said elements, each protuberance having a pair of upper diverging nail bending walls and a bottom nail holding wall and each two adjacent protuberances having a nail receiving passage therebetween and forming a pair of straight converging nail bending walls therebetween, the converging nail bending walls defining a funnel shaped entrance to the nail receiving passage so that the forward extremity of a nail driven into the nailing groove and into a nail receiving passage will strike against the nail bending wall of one of the protuberances and be bent in the plane of the groove and into holding engagement with the bottom wall of an adjacent protuberance which holds the nail against withdrawal by resistance of the bent nail extremity to straightening.

8. A one-piece structural member formed from a single metal sheet for receiving and retaining nails, staples and the like, said structural member comprising a web element; a flange integral with and extending along one edge of said web element; a nail guiding element integral with said flange, said nail guiding element being spaced from and parallel with said web element to form a nailing groove therewith; guide means for maintaining a nail driven into said nailing groove normal to said flange, said guide means including a series of nail entering passages in said flange opening into said nailing groove, the wall of each entering passage gripping a nail en-

tering said nailing groove through the passage, and a series of nail gripping bosses formed on one of said elements, each pair of adjacent bosses forming a nail guiding passage substantially in line with one of said entering passages; and means for bending the forward extremity of a nail in the plane of the nailing groove and for holding the same against withdrawal, said last mentioned means including a series of protuberances formed on one of said elements, and each protuberance having a pair of upper diverging nail bending walls and a bottom nail holding wall; each two adjacent protuberances having a nail receiving passage therebetween and forming a pair of straight converging nail bending walls therebetween defining a funnel shaped entrance to the nail receiving passage, the funnel shaped entrance having its apex substantially in line with one of said bosses so that the forward extremity of a nail driven into the nailing groove and into a nail receiving passage will strike against the nail bending wall of one of the protuberances and be bent in the plane of the groove and into holding engagement with the bottom wall of an adjacent protuberance which holds the nail against withdrawal by resistance of the bent nail extremity to straightening.

9. A one-piece structural member formed from a single metal sheet for receiving and retaining nails, staples and the like, said structural member comprising a web element; a flange integral with and extending along one edge of said web element; a nail guiding element integral with said flange, said nail guiding element being spaced from and parallel with said web element to form a nailing groove therewith; a series of entering passages in said flange opening into said nailing groove; a series of nail gripping bosses formed on one of said elements, each adjacent pair of bosses forming a nail guiding passage therebetween; and means for bending the forward extremity of a nail in the plane of the nailing groove and for holding the same against withdrawal, said last mentioned means including a series of protuberances each having a pair of upper diverging nail bending walls and a bottom nail holding wall, each two adjacent protuberances having a nail receiving passage therebetween and forming a pair of converging nail bending passages therebetween defining a funnel shaped entrance to the nail receiving channel, the funnel shaped entrance extending across a plurality of said nail guiding passages and having its apex substantially in line with one of said bosses so that the forward extremity of a nail driven into the nailing groove will strike against the nail bending wall of one of the protuberances and be bent into holding engagement with the bottom wall of an adjacent protuberance which holds the nail against withdrawal by resistance of the bent nail extremity to straightening.

10. A one-piece structural member formed from a single metal sheet for receiving and retaining nails, staples and the like, said structural member comprising a web element; a flange integral with and extending along one edge of said web element; a nail guiding element integral with said flange, said nail guiding element being spaced from and parallel with said web element to form a nailing groove therewith; a series of entering passages extending through said flange and opening into said nailing groove; a series of spaced bosses formed on said web element; a similar series of spaced bosses formed on said nail guiding element, said two series of bosses being

opposite each other and each two opposite pairs of adjacent bosses forming a nail guiding passage in line with one of said entering passages; and means for bending the forward extremity of a nail in the plane of the nailing groove and for holding the same against withdrawal; said last mentioned means including a series of protuberances formed on one of said elements and a similar opposite series of protuberances formed on the other one of said elements, each two adjacent pairs of opposite protuberances having a nail receiving passage therebetween and forming a pair of converging nail bending walls therebetween, the converging nail bending walls defining a funnel shaped entrance to the nail receiving passage so that the forward extremity of a nail driven into the nailing groove and into a nail receiving passage will strike against the nail bending wall of one of the protuberances and be bent in the plane of the groove and into holding engagement with an adjacent pair of opposite protuberances which hold the nail against withdrawal by resistance of the bent nail extremity to straightening.

11. A one-piece structural member formed from a single metal sheet for receiving and retaining nails, staples and the like, said structural member comprising a web element; a flange integral with and extending along one edge of said web element; a nail guiding element integral with said flange, said nail guiding element being spaced from and parallel with said web element to form a nailing groove therewith; and means for bending the forward extremity of a nail in the plane of the nailing groove and for holding the same against withdrawal, said last mentioned means including a series of protuberances formed on one of said elements, each protuberance having a pair of upper diverging nail bending walls and a bottom nail holding wall and each two adjacent protuberances having a nail receiving passage therebetween and forming a pair of straight converging nail bending walls therebetween, the converging nail bending walls defining a funnel shaped entrance to the nail receiving passage so that the forward extremity of a nail driven into the nailing groove and into a nail receiving passage will strike against the nail bending wall of one of the protuberances and be bent in the plane of the groove and into holding engagement with the bottom wall of an adjacent protuberance which holds the nail against withdrawal by resistance of the bent nail extremity to straightening, said last mentioned means including a nail guide in said funnel shaped entrance in line with the nail receiving passage to guide the forward extremity of the nail into the nail receiving passage.

12. A one-piece structural member formed from a single metal sheet for receiving and retaining nails, staples and the like, said structural member comprising a web element; a flange integral with and extending along one edge of said web element; a nail guiding element integral with said flange, said nail guiding element being spaced from and parallel with said web element to form a nailing groove therewith; guide means for maintaining a nail driven into said nailing groove normal to said flange, said guide means including a series of nail entering passages in said flange opening into said nailing groove, the wall

of each entering passage gripping a nail entering said nailing groove through the passage, and a series of nail gripping bosses formed on one of said elements, each pair of adjacent bosses forming a nail guiding passage substantially in line with one of said entering passages; and means for bending the forward extremity of a nail in the plane of the nailing groove and for holding the same against withdrawal, said last mentioned means including a series of protuberances formed on one of said elements, and each protuberance having a pair of upper diverging nail bending walls and a bottom nail holding wall; each two adjacent protuberances having a nail receiving passage therebetween and forming a pair of straight converging nail bending walls therebetween defining a funnel shaped entrance to the nail receiving passage, the funnel shaped entrance having its apex substantially in line with one of said bosses so that the forward extremity of a nail driven into the nailing groove and into a nail receiving passage will strike against the nail bending wall of one of the protuberances and be bent in the plane of the groove and into holding engagement with the bottom wall of an adjacent protuberance which holds the nail against withdrawal by resistance of the bent nail extremity to straightening, the boss in alignment with said apex having an extended guide portion to guide the bent extremity of the nail into the nail receiving passage.

13. A one-piece structural member formed from a single metal sheet for receiving and retaining nails, staples and the like, said structural member comprising a web element; a flange integral with and extending along one edge of said web element; a nail guiding element integral with said flange, said nail guiding element being spaced from and parallel with said web element to form a nailing groove therewith; guide means for maintaining a nail driven into said nailing groove normal to said flange, said guide means including a series of nail entering passages in said flange opening into said nailing groove, the wall of each entering passage gripping a nail entering said nailing groove through the passage, and a series of nail gripping bosses formed on one of said elements, each pair of adjacent bosses forming a nail guiding passage substantially in line with one of said entering passages; and means for bending the forward extremity of a nail in the plane of said groove and for holding the same against withdrawal by resistance of the bent nail extremity to straightening, said last mentioned means including a series of nail bending and holding protuberances, each adjacent two protuberances coacting to bend and hold a nail.
